UNITED STATES PATENT OFFICE.

GEORGE H. TAGGART, OF NEW YORK, N. Y.

AUTOMATIC STOP FOR PHONOGRAHS.

1,286,833.

Specification of Letters Patent.

Patented Dec. 3, 1918.

Application filed March 5, 1918. Serial No. 220,479.

To all whom it may concern:

Be it known that I, GEORGE H. TAGGART, a citizen of the United States, and a resident of the city of New York, borough of Manhattan, in the county and State of New York, have invented a new and Improved Automatic Stop for Phonographs, of which the following is a full, clear, and exact description.

10 This invention relates to phonographs and has particular reference to means for automatically stopping the machine when the end of a record or the like is reached.

The primary object of the invention, 15 therefore, is to provide automatic means of an improved and simplified character whereby the turntable of a phonograph will be stopped practically instantly when the needle ceases to move toward the center of 20 the turntable by virtue of the spirality of the groove of the record.

More definitely stated and among the other objects, my invention has in view the provision of simple, reliable and inconspicuous mechanism, that requires no adjustment or attention on the part of the operator after it is once applied to the machine, but which will automatically stop the motor when the 25 end of the record is reached, irrespective of 0 the size of the standard disk or length of the record, and which is not subject to premature stoppage from any cause.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a plan view of a phonograph cabinet with its tone arm and reproducer and indicating in dot and dash lines the approximate position of the turntable, the principal features of my improvement being located beneath the turntable.

Fig. 2 is a vertical sectional view on the line 2-2 of Fig. 1.

Fig. 3 is an enlarged detail view of the brake actuating means with parts in section on the line 3-3 of Fig. 2.

Fig. 4 is a vertical transverse section on the line 4-4 of Fig. 1;

Fig. 5 is a similar view of the turntable driving means on the line 5-5 of Fig. 1.

Fig. 6 is a detail plan view of a changed position of the cam mechanism; and

Fig. 7 is a detail view as would be seen from the plane of the line 7-7 of Fig. 1.

Referring now more particularly to the drawings I show at 10 the deck of a phonograph of any approved or conventional construction, having a hole 11 through which the spindle 12 is operated from any suitable motor, not shown, for rotating the turntable 13 upon which the disk 14 is centered and supported as usual. The tone arm 15 is 65 adapted to oscillate around the vertical axis of the elbow of a socket 16 and carries at its outer end as usual any suitable reproducer 17 carrying a needle 18 coöperating with the spiral record groove of the disk record. 70 The term "disk" as used herein is applicable to the physical body, while the groove will be referred to as the record. It will be understood that the parts thus far described are or may be of any well known or approved construction and that my improvement described in detail below is adapted to be attached to any such construction. 75

The brake comprises a shoe 19 mounted on a vertical pivot 20 on a lever 21 having 85 a fixed pivot 22 connected to any suitable base or plate beneath the turntable, the shoe, however, being adapted to act inward against the flange 13' of the turntable to stop the motion thereof, under the force of 90 a relatively strong spring 23 fixed at one end at 24 to the lever and at its other end to an adjustable plate 25. The brake in the normal running position of the machine is held slightly spaced from the turntable 95 flange by an anti-friction trigger device comprising a bell crank lever 26 mounted on a fixed vertical pivot 27. One arm 28 of the bell crank 26 carries an anti-friction roller 29 mounted on a pivot 30 and bearing 100 normally against the shouldered end 31 of the lever 21, the point of contact between the lever 21 and the roller 29 being substantially in alignment with the axes of the pivots 27 and 30 so that even though the spring 105 23 draws with considerable force upon the lever 21 the brake will not be set until the equilibrium of the anti-friction roller in its normal position is disturbed by some external influence. 110

The bell crank 26 has two other arms 32 and 33, the former extending from the pivot

27 laterally toward the spring 23 or substantially parallel to the lever 21. The other arm 33 extends on the opposite side of the pivot 27 from the arm 32 and approximately 5 diametrically opposite the bisector of the angle between the arms 28 and 32. In other words the arms 28 and 32 are arranged approximately at right angles to each other and the arm 33 is arranged approximately 10 135 degrees from each of them.

Any suitable means may be provided to push outward on the free end of the arm 32 to rotate the bell crank in a clockwise direction around its pivot 27. Because of the anti-friction roller 29 the force necessary to so 15 initiate the rotation of the bell crank may be relatively slight, for after the slightest movement the force of the main spring 23 will continue such rotation of the bell crank 20 allowing the brake to be set. The dotted lines of Fig. 3 indicate the set position of the 25 brake and the trigger mechanism and indicating how the arm 33 is then projected inward more directly toward the center of the turntable.

34 indicates a circular arc shaped bar or actuator mounted for reciprocation in a circular arc whose center is the vertical axis 16. This actuator 34 is guided for such reciprocations along guideways 35 of any suitable nature and it is adapted to be so reciprocated by connection with any desired part of the tone arm construction which in the 30 normal manipulation and operation of the machine is oscillated around said vertical axis 16. In the form of the invention shown the connection between the tone arm structure and the actuator 34 is effected through a suitable arm 36 fixed upon the tone arm 40 and reaching outward and having any suitable lost motion connection at its lower end with the end 34' of the actuator remote from the brake mechanism. It will be understood that when the tone arm is moved to the right 45 preliminary to introducing a disk 14 to the turntable the actuator will be moved in a corresponding direction until it is stopped by any suitable lug or the like such as indicated at 37, and when the tone arm is moved to the left either by the operator for any 50 purpose or during the normal running of the machine with the needle 18 in the spiral groove of the disk the actuator 34 will be moved likewise toward the left and at the 55 same angular velocity as the tone arm.

38 indicates a trip lever pivoted on the pivot 40 and adjacent to the U-shaped arm 39 within which the bell crank 26 is mounted. The main portion of the lever 38 comprises a long arm the main portion of which is straight and just below an extension of the upper half of the U-shaped arm 39, the extension being inward toward the axis of the post 12 but slightly eccentric thereto, 60 while the extreme inner end 38' of the lever

is deflected approximately toward said post 12. On pivot 40 spanning the two legs of the U-shaped arm 39 is mounted a knuckle 41 having tooth 42. The lower portion of the arm 39 has attached to the free end 70 thereof at 43 a light spring 44 anchored at its inner end to an adjustable plate 45, the tendency of the spring being to swing the trip lever 38 in a counter clockwise direction around its pivot 27. 75

The longer portion of the trip lever 38 constitutes a holder or carrier for a thrust member indicated herein as comprising a wire 46 having loose looped engagement at its inner and outer ends at 47 and 48 with 80 the straight portion of the lever 38 and provided intermediate of its ends with a coil 49 for additional flexibility. The extreme inner end 50 of the thrust member lies just below the horizontal plane of the lever 38 and 85 its inward extension 38' but otherwise is parallel to the axis of the main portion of the lever 38. The end loop 48 lies against or close to the free end 32 of the trigger bell crank 26 and so when any force is applied 90 to the inner end 50 of the thrust member forcing it outward such force tends to throw the anti-friction roller out of normal position.

Any suitable means, depending preferably 95 on the rotation of the turn table, may be provided to actuate or control the thrust member 46. To this end I show herein a lever 51 pivoted on a fixed pivot 52 and having a shoe 53 held normally in contact 100 with the periphery of a cam wheel 54 journaled on a vertical pivot 55 at one side of the post 12. Nearly all of the periphery of said cam wheel is circular and concentric with the pivot 55, but there is provided a 105 cam 56 and adjacent thereto is a corresponding depression 57. The shoe 53 is held normally against the periphery of this cam wheel by means of a spring 58. The main portion of the lever 51 is arranged approximately at right angles to the trip lever 38 but it is provided with a finger 59 extending therefrom at an oblique angle substantially intersecting the deflected end 38' of the trip lever. A shoe 59' carried by the outer end 110 of the finger bears against the side of the extension 38' remote from the spring 58. The wheel 54 may be of any suitable size or design and variously located for its purpose, it being noted, however, that it is rotated continuously in the direction indicated by the arrows as long as the turntable is 115 rotating. The means illustrated for driving the wheel 54 comprises a friction wheel 60 whose periphery bears against a concentric hub 61 of the wheel 54. At each rotation of the wheel 54 the cam 56 thereof strikes the shoe 53 and so swings the lever 51 outward in a clockwise direction to a distance 120 equal to the throw of the cam. The outer 125

65 130

portion of the shoe 53 at this time is thrown into the dotted line position of Fig. 1, past the end 50 of the thrust member, the shoe 59' being carried at this time away from the end

- 5 38' of the trip lever, not bearing against any other part. While the cam 56 passes beyond the shoe 53 the spring 58 draws said shoe promptly into the recess 57, but in so doing the shoe 59' wiping against the extension 38' 10 swings both the trip lever 38 and the member 46 far enough toward the pivot 52 to bring the point 50 of the thrust member into the path of the shoe 53 where it would be struck by said shoe 53 on the next actuation 15 thereof by the cam 56 unless the thrust member in the meantime be restored to its normal position.

The means I provide to automatically and normally maintain the thrust member point 20 50 out of the path of the shoe 53 comprises a friction shoe 62 bearing against the inner edge of the curved actuator bar 34 and held in such position by means of the teeth 42 extending from the knuckle 41 above described, it being noted that the shoe 62 lies between the axis 40 of the knuckle and said actuator bar so that the light spring 44 acting constantly upon the free end of the U-shaped member 39 of the trip lever will always maintain this position. It is to be borne in mind that the spiral record groove in its coöperation mechanically with the needle 18 will cause, by reason of the rotation of the turntable, a constant translation 30 of the needle toward the center of the disk and from this fact it follows that the tone arm acting through the support 36 will move the actuator bar 34 constantly though at a low rate of speed in the same direction. This 40 frictional engagement between the bar 34 and the shoe 62 acting on what may be termed a relatively short arm of the lever 38 between the point or surface of contact of the actuator and the center of the pivot 45 40 will be so multiplied out at the end of the longer arm of the lever 38 that the relatively slight movement of the actuator bar incident to each rotation of the disk will be sufficient to normally keep the point 50 of the thrust member out of the path of the shoe 53. When, however, the aforesaid lateral 50 translation of the needle ceases from any cause as for instance when the needle reaches the inner end of the record and runs into the 55 concentric portion thereof the actuator bar will no longer be functional to cause the swinging of the longer end of the lever 38 and point 50 of the thrust member toward the left. Therefore, while the wheel 54 on 60 its next rotation will occasion through its depression 57 the actuation by means of the spring 58 of the point 50 toward the right or into the path of the shoe 53, said point 65 will remain in such position where it will be impinged against by said shoe 53 on the next

approach of the cam 56 thus immediately tripping the brake and stopping the turntable.

On the next oscillation of the tone arm toward the right preliminary to starting the 70 next record the actuator bar 34 will be moved therewith and thereby in a similar direction until stopped as by means of the lug 37. During this movement of the bar 34 a lug or rib 63 formed thereon wipes 75 against the free end of the arm 33 of the trigger member and so swings said trigger member in a counter clockwise direction and brings the anti-friction roller 29 between the free end of the brake lever 31 and the pivot 80 27, thus releasing the brake where it will be held positively by virtue of the rib 63 so long as the actuator bar is at its extreme throw to the right or approximately so. The rib 63 may be of any suitable length 85 but preferably is so located or proportioned that it will have coöperation with the end of the arm 33 during enough of the first portion of the rotation of the disk to insure that the record will be well started before 90 the rib 63 passes to the left beyond the arm 33. It will thus be appreciated that while the operator is manipulating the reproducer and setting the needle there will be no danger of such stoppage of oscillation of the 95 tone arm as will initiate the setting of the brake due to the failure of continued movement of the actuator bar. In other words for normal playing purposes the operator will go through practically the same 100 motions that he usually does in respect of a machine having no automatic means for stopping the turntable. That is, he swings the tone arm to the right, changes the disk or needle if necessary, and then applies the needle to the record. By this time the turntable will have started in its rotation and as required at the proper speed. The operator then may rest at ease without concern about stopping the machine at the end of the 110 record.

I claim:

1. In an automatic stop for phonographs, the combination with a rotating part, a brake coöperating therewith to stop the rotation thereof, and power means acting upon said brake member tending to make it effective, of a trigger member comprising a pivoted lever and an anti-friction roller acting between the brake member and the power 115 means acting thereon, said anti-friction member being located normally approximately in a direct line between its point of contact with the brake member and the axis of the pivoted member, a member for turning the pivot member on its axis to throw the anti-friction member out of said line, and means actuated by the rotation of said rotating member to actuate the member acting on the pivoted member.

4

2. In an automatic stop for phonographs, the combination with a turntable, a brake shoe coöperating therewith to stop the turntable, a lever carrying said shoe, and a spring acting upon the lever to apply the shoe, of trigger mechanism to control the setting of the brake and comprising a pivoted lever and an anti-friction roller journaled on one arm of the lever and lying normally with its axis in a substantially straight line between the axis of the trigger lever and the point of contact between the roller and the brake lever, a cam member rotated coincidentally with the turntable, thrust means between the cam member and the trigger lever for rotating the trigger lever and tripping the brake, and means coöperating with the tripping means aforesaid preventing the operation thereof while the record is being played.

3. The combination with a turntable for supporting a record disk having a spiral

groove, a brake shoe coöperating with the turntable, means acting upon the shoe tending to apply it to the turntable, and reproducer means coöperating with the disk groove and moved by the groove laterally over the disk while the record is being reproduced, of trigger mechanism coöperating normally with the brake shoe to hold it spaced from the turntable, a cam device actuated by the turntable, thrust means between the cam device and the trigger devices, and an actuator member moved coincidentally with the sound reproducing means coöperating with the thrust member serving to prevent the operation of the thrust member while the sound reproducing means are being translated by the groove, but serving to cause the actuation of the trigger mechanism through the thrust member when the sound reproducing means no longer is translated.

GEO. H. TAGGART.
